UNITED STATES PATENT OFFICE

HAROLD E. JACKSON, OF DETROIT, MICHIGAN

SHOCK ABSORBER

Application filed February 25, 1928. Serial No. 256,852.

My invention relates to an improved shock absorber of the fluid compression type and particularly to such an article adapted for use on a motor vehicle to absorb the road shocks incident to travel of the vehicle.

An object is the provision of a shock absorber of the character described adapted to check the throw of the car body both up and down and which is so constructed as to be capable of adjustment to vary the resistance imposed by the absorbing mechanism in either of said directions of movement and to vary the ratio therebetween.

A meritorious feature lies in the provision of mechanism of this type having two compression chambers communicating through an intermediate chamber within which compression mechanism is operatively disposed to be actuated to exert a pressure upon the fluid in each compression chamber, and having controlled outlets for fluid from both compression chambers into the intermediate chamber each of which outlets is adjustable to vary the restriction imposed thereby upon the flow of fluid and adjustable independently from the exterior of the casing.

A point of value resides in the provision of novel valve mechanism operable to vary the restriction of the liquid outlet passageway from each compression chamber.

Other advantages and meritorious features of my invention will more fully appear from the following specification, appended claims and accompanying drawings, where-

35 in—

Fig. 1 is a cross-sectional view taken on line 1—1 of Fig. 2.

Fig. 2 is a cross-sectional view taken on line 2—2 of Fig. 1.

40 Fig. 3 is an enlarged fragmentary sectional view through the valve mechanism.

Fig. 4 is an elevation of a fragment of the casing showing the valve adjustment.

45 Fig. 5 is an enlarged rear end view of one of the pistons.

Fig. 6 is a cross-sectional view taken on line 6—6 of Fig. 4.

50 My improved shock absorber is mounted upon the vehicle in the conventional manner and is provided with a lever 10 which

is coupled up with the vehicle so that the mechanism is adapted to absorb the throw of the vehicle body with respect to the axle. There is a casing 12 adapted to contain a suitable liquid and provided with a cover plate 55 14 secured thereto by screws 16 or in any suitable fashion. This casing may be fastened to its point of support by studs 18 and it is divided into three compartments.

The two end compartments, indicated as 20 and 22, constitute compression chambers and the intermediate compartment, indicated as 24, is in communication with each of the end compartments and serves as a reservoir for 65 liquid. Each end compartment has an air dome 26 above the liquid level within which air is trapped, and is a preferred form of construction.

This liquid level is indicated in Fig. 1 by 70 the dotted line α — α .

Each compression compartment communicates with the intermediate compartment through a cylinder 28. A piston 30 is mounted for reciprocation within each cylinder 28. 75 These two pistons are here shown as connected for joint operation and as constituting a double end piston combination actuated by an arm 32 mounted upon a shaft 34 coupled with the arm 10 to be actuated 80 thereby.

The pistons are similar in construction and each piston is hollowed out as shown in Fig. 1 and is provided with a plurality of passageways 36, four being a suitable number, extending angularly through the head of the piston and terminating in a common passageway 38, the outlet of which toward the rear of the piston is normally closed by a ball check valve 40 held thereagainst by a spring 42 mounted within a cage 44 provided with a vent 46. This cage is hat shaped and has a brim or flange portion 48 which seats within the cored-out portion 50 of the piston and is held therein by a snap ring 52. This flange 95 portion has passageways 54 extending therethrough to permit the passage of fluid from the intermediate chamber into the compression chamber upon the unseating of the ball valve 40. 100

When the piston travels outwardly away from the compression chamber 20, this ball check valve 40 is unseated as the spring 42 is a very light spring and fluid passes readily into the compression chamber through the openings 36, 38 and 54. The opening 46 is merely to provide a vent back of the ball check.

Each compression chamber exhausts into the intermediate chamber through a controlled passageway below the normal liquid level the restriction of which is regulated by valve mechanism of the following type:

There is a tubular member 56 which extends from the exterior of the casing through the intermediate chamber 24 and into the compression chamber 20, being threaded at one end as at 58 for threaded adjustment into said compression chamber. This tubular member is provided with a central passageway 60 as shown, having radial outlets 62 through which fluid passes from the compression chamber to the intermediate chamber:

The flow of fluid through this passageway is regulated by a valve element 64 held by a spring 66 to a determined position within the adjustable tubular member 56, which position is here determined by a nipple 68 which engages the wall of the casing as shown in Figs. 3 and 6. This valve element 64 is shown in Figs. 3 and 6 as having axial passageways 65, four equally spaced ones being here shown, to permit the flow of lubricant therewith to escape from the compression chamber. These axial passageways however, do not determine the controlled restriction but this is determined by the relative position of an annular flange portion 70 carried by said valve element 64 which flange portion is held to measure a restriction against outlets 62 formed through the tubular member 56.

It will be seen that adjustment of the tubular member 56 with respect to the fixed idle position of the valve member 64 as determined by the spring 66 holding said valve member with its nipple bearing against the casing wall will vary the restriction formed by the position of said flange 70 with respect to said outlets 62 and that this adjustment is accomplished by rotating the tubular member 56 to increase or decrease said restriction. The tubular member is positioned within a threaded lock nut 72 and has an end flange 74 serrated as shown in Fig. 4 providing notches 76 within which a releasable lock member 78 held by a screw 80 may seat to determine the adjustment of the valve.

It will now appear that the flow of liquid from each compression chamber may be regulated to a fine point and independently of the flow of liquid from the other compression chamber and that this adjustment is made from a point exteriorly of the casing and may be effected in determined graduated amounts

to provide the required resistance to the movement of the piston. It is therefore possible not only to regulate the resistance imposed upon the piston in either direction of movement of the body of the vehicle which actuates the piston, but likewise to vary the ratio in opposite directions.

It will be seen that this shock absorber is of the type wherein the initial movement is cushioned by the air pocket and the continuation of such movement is taken up by the exhaust of liquid against the provided restriction.

What I claim is:

1. A shock absorber having a pair of high pressure fluid compression chambers connected by a low pressure communicating cylinder, a double acting piston assembly mounted within the cylinder for reciprocation to exert a pressure upon the fluid in each chamber, each chamber provided with a restricted outlet regulating the flow of fluid therethrough to the other chamber, a valve extending through the outer wall and a portion of the low pressure cylinder controlling each outlet and adjustable to regulate the flow of liquid therethrough within a determined pressure and automatically releasable to increase such flow above a determined pressure.

2. A shock absorber having a casing divided into two liquid compression chambers chamber into each compression chamber, a cylinder extending from the intermediate chamber into each compression chamber, a double acting piston assembly within the cylinder, a liquid medium within the casing submerging the piston assembly means within the intermediate chamber engaging the piston assembly to reciprocate it to exert a pressure on the fluid in each compression chamber, each compression chamber provided with an air dome arranged in the uppermost portion thereof above the piston assembly and provided with an independently controlled restricted outlet below the air dome and below the normal liquid level for the flow of liquid therethrough into the intermediate chamber whereby the relative ratio of the discharge of the two compression chambers into the intermediate chamber may be varied, said independent control including a valve extending through the outer wall and intermediate chamber into the compression chamber.

3. A shock absorber having a casing providing two chambers, one chamber constituting a liquid reservoir and the other chamber constituting a liquid compression chamber communicating with the reservoir to receive liquid therefrom, means operable to exert a pressure upon the liquid in the compression chamber, a tubular member leading from the compression chamber through the reservoir and through the wall of the casing providing

- a passageway for liquid from the compression chamber into the reservoir, a valve element supported within said tubular member to regulate the flow of liquid through said tubular member from the compression chamber into the reservoir, said tubular member adjustable exteriorly of the casing to regulate the restriction imposed by said valve element upon the flow of liquid through the opening. 5
4. A shock absorber having a casing providing two chambers, one chamber constituting a liquid reservoir and the other chamber constituting a liquid compression chamber communicating with the reservoir to receive liquid therefrom, means operable to exert a pressure upon the liquid in the compression chamber, a tubular member leading from the compression chamber through the reservoir and through the wall of the casing providing 15 a passageway for liquid from the compression chamber into the reservoir, a valve element supported within said tubular member under yieldable pressure at a determined position to regulate the flow of liquid through 20 said tubular member and automatically responsive to a determined increase of liquid pressure within the compression chamber to increase the flow of liquid through the tubular member, said tubular member being adjustable to vary the restriction imposed 25 thereon by the valve element. 30
5. A shock absorber having a casing providing two chambers, one chamber constituting a liquid reservoir and the other chamber 35 constituting a liquid compression chamber communicating with the reservoir to receive liquid therefrom, means operable to exert a pressure upon the liquid in the compression chamber, a tubular member leading from the 40 compression chamber through the reservoir and through the wall of the casing providing a passageway for liquid from the compression chamber into the reservoir, a valve element supported within said tubular member 45 and held under spring pressure to a determined position therein to regulate the flow of liquid therethrough and automatically responsive to a determined liquid pressure within the compression chamber to permit 50 an increased flow of liquid therefrom, said tubular member being threadedly mounted for adjustment exteriorly of the casing to vary the restriction imposed thereupon by the valve element. 55
6. A shock absorber comprising a casing divided into two end compartments separated by and communicating with an intermediate compartment, a cylinder extending from the intermediate compartment into 60 both end compartments, each end compartment provided with an air dome communicating therewith and positioned above said cylinder, a liquid medium in the casing submerging the cylinder, reciprocating piston 65 mechanism mounted in the cylinder for oper- 70
- ation to exert pressure upon the liquid in either end compartment, valve mechanism for each end compartment arranged substantially below the air dome and controlling the flow of liquid from the intermediate compartment into the end compartment, and valve mechanism for each end compartment arranged substantially below the air dome thereof controlling the flow of liquid therefrom into the intermediate compartment, 75 said last named valve mechanism extending through the wall of the casing into the intermediate compartment and through the intermediate compartment to regulate the outlet from the end compartment. 80
7. A shock absorber comprising, in combination, a pair of high pressure compression chambers connected by a low pressure communicating cylinder, a double acting piston assembly mounted within the cylinder for reciprocation to exert a pressure upon the fluid in each chamber, a restricted passageway leading from each of the high pressure compression chambers into the low pressure cylinder, and means extending 85 through the absorber casing wall and through the low pressure cylinder adjustable exteriorly of the casing to vary the passageway leading from the high pressure to the low pressure cylinder. 90
- In testimony whereof, I HAROLD E. JACKSON, sign this specification.
